CLAIM

I claim the ornamental design for a cover for a lintel or angle iron, as shown and described.

DESCRIPTION

FIG. 1 is a perspective view of a cover for a lintel or angle iron, showing my new design;

FIG. 2 is front view of the cover for a lintel or angle iron;

FIG. 3 is a back view of the cover for a lintel or angle iron;

FIG. 4 is a left-side view of the cover for a lintel or angle iron;

FIG. 5 is a right-side view of the cover for a lintel or angle iron;

FIG. 6 is a bottom view of the cover for a lintel or angle iron;

FIG. 7 is a top view of the cover for a lintel or angle iron;

and,

FIG. 8 is a perspective view of the cover for a lintel or angle iron, shown in a state of use.

The broken lines in FIG. 8 represent environmental subject matter only and form no part of the claimed design. The cover for a lintel or angle iron is shown with a symbolic break in its length. The appearance of any portion of the cover for a lintel or angle iron between the break lines forms no part of the claimed design.
